UNITED STATES PATENT OFFICE.

ELIJAH F. SPAULDING, OF TROY, NEW YORK, ASSIGNOR TO RUDOLPH F. EMMERICH, OF BROOKLYN, NEW YORK.

COIN-CONTROLLED VENDING-MACHINE.

No. 810,576.

Specification of Letters Patent.

Patented Jan. 23, 1906.

Application filed May 19, 1905. Serial No. 261,143.

To all whom it may concern:

Be it known that I, ELIJAH F. SPAULDING, a citizen of the United States, and a resident of Troy, in the county of Rensselaer and State of New York, have invented certain new and useful Improvements in Coin-Controlled Vending-Machines, of which the following is a specification.

The invention relates to improvements in coin-controlled vending-machines; and it consists in the novel features, arrangements, and combinations of parts hereinafter described, and particularly pointed out in the claims.

15 The object of the invention is to provide a more efficient and convenient vending-machine than those heretofore known and also one composed of comparatively few parts, easily assembled, and inexpensive of manufacture. A further object of the invention is to provide a machine capable of testing the coins submitted to it both as to their size and weight and of refusing to discharge the confections or the like when such coins are deficient either as to size or weight.

20 The machine of my invention also comprises means for discarding washers, steel disks, and the like, which are frequently fed to vending-machines in attempts to cheat the same.

25 My invention comprises a novel construction of casing or cabinet and holders for the stacks of confections or other articles and also novel operative mechanism, the latter being preferably carried by a tiltable and also removable front section, wherein are provided the coin-slots and slots for the operating-levers.

30 The invention will be fully understood from the detailed description hereinafter presented, reference being had to the accompanying drawings, in which—

35 Figure 1 is a front view, partly broken away, of a vending-machine constructed in accordance with and embodying the invention, one of the operating-levers being shown in its operated or depressed position. Fig. 2 is a side elevation, partly in section, of same, the side of the casing having been removed and a 40 portion of the machine being in section on the dotted line 2 2 of Fig. 1. Fig. 3 is a front elevation, partly broken away, of the machine with a section of the front casing removed to

disclose the operative mechanism. Fig. 4 is a view corresponding with Fig. 2, but illustrating the operating-lever in its depressed position. Fig. 5 is a detached vertical section on the dotted line 2 2 of Fig. 1 of the front casing, which carries the operative mechanism of the machine, and illustrates said mechanism in side elevation and in a partly-operated position dislodging a steel disk which was introduced into the machine in lieu of a copper cent. Fig. 6 is a view corresponding with Fig. 2, but illustrating the holder for the 45 stack of confections in an elevated position to be replenished and the operative mechanism of the machine, with the front casing carrying the same, as having been tilted inwardly to dislodge the accumulated coins. Fig. 7 is a view corresponding with Fig. 2, with the full height of the machine shown and the interior operative mechanism omitted. Fig. 8 is a side elevation of the device for testing the coins and ejecting the pieces of chocolate or 50 the like from the stack thereof. Fig. 9 is a top view of same, and Fig. 10 is a front elevation of same.

55 In the drawings, 15 designates the general casing or cabinet of the machine, this casing comprising rigid sides 16, a bottom 17, a top 18, a back 19, a removable front 20, having a glass panel 21, and a lower metallic front section 22, preferably of cast metal, having at its lower end an inwardly-turned portion 23, upon which the coins are finally received and below which is formed the passage 24, through which the purchased pieces of chocolate or other material may be removed in the customary manner. The inner edge of the 60 member 23 of the cast section 22 normally engages the lower end of a transverse bar 25, which is rigidly secured to the sides 16 and which prevents the lower end of the section 22 from being pressed inwardly and also prevents access to the receiving-chamber formed above said portion 23. The transverse bar 25 cooperates with the section 22 in forming the chamber to receive and confine the coins which may be fed to the machine. The upper edge of the bar 25 is provided with a strip of metal 26, upon which the ejectors, herein-after described, may have a sliding movement, this bar 26 serving to protect the bar 25 from being worn by the movement of said 65 ejectors, but not being necessary to my in-

vention, since the ejectors being very light will not appreciably wear the bar 25, which is preferably of wood.

The upper edge of the cast section 22 is of angular formation, as shown, to engage the lower angular outer edge of the front 20, which when in position will prevent the upper end of the section 22 from being turned inwardly, the bar 25 and front 20 operating 10 as stops to lock the section 22 in rigid position. The section 22 is supported upon a shaft 27, which at its ends is mounted in bearing-plates 28, secured to the inner faces of the sides 16, and is confined wholly within the 15 general frame of the machine. The shaft 27 passes through rigid arms 29, cast with the section 22, and thus is enabled to support said section, the latter being rigidly held when the front 20 is in position, but being capable of being turned inwardly upon the shaft 27, as shown in Fig. 6, when said front is removed from the machine.

The front 20 is simply a rectangular frame having a glass panel and closely fitting between the sides 16 and below the top 18 and supported at its lower end upon studs 30, which extend inwardly from the sides 16, as indicated in Fig. 1, and receive the hooks 31, secured to said front 20. The upper end of 25 the front 20 is equipped with a suitable lock 32, by which it may be secured to the top 18, the key to this lock to be held by the owner of the machine. The front 20 will also be provided with a stop-piece 33, which when 30 the said front is introduced to position will abut against the holders 34 for the stacks of chocolates or other articles.

Below the transverse bar 25 and inwardly-extending portion of the section 22 is provided a metallic runway 35 of usual character for directing the dislodged pieces of chocolate or other material toward the front of the machine and into the discharge-space 24.

The holders 34 for the stacks of chocolates or other articles comprise a back, sides, and inwardly-extending front flanges 36, which will embrace the ends of the pieces of chocolate 37, as shown in Fig. 3. The holders 34 are not in their general structure of unusual 40 formation, and they are open at their front, so that the chocolates or other articles stacked in them may be observed through the glass panel of the front 20. The holders 34 are fastened together, as by solder or the like, at 45 their meeting sides, and in the present instance I illustrate two of such holders. The group of holders 34 constitute, in effect, an integral frame, and said frame is supported upon the end portions of the shaft 27 by 50 means of hook-brackets 28, these brackets 38 permitting the removal of the said frame when desired. The brackets 38 are of cast metal and integral with a transverse connecting-bar 39 and supporting-fingers 40, the latter projecting inwardly below the outer edges 55

of each holder 34 to a sufficient extent to support the stack of chocolates therein without interfering with the removal of said chocolates from the lower end of the holder during the operation of the machine. The frame of holders 34 is therefore detachably supported from the shaft 27 and is normally maintained in a vertical position by the engagement with its upper end of the stop-piece 33, carried by the front 20, and also by the blocks 41, Fig. 7, secured to the back 19 of the machine-frame. 70

The frame or group of holders 34 may be detached from the shaft 27 when the front 20 is unlocked and removed from the machine, and in Fig. 6 I illustrate the holders 34 as 80 having been detached from the shaft 27 and supported upon the studs 30, which had previously supported the said front 20, the hook-brackets 38, carried by the holders 34, having been hooked upon said studs. When the 85 frame or group of holders 34 is mounted upon the studs 30, the said frame will stand in an inclined position, due to the presence of the top 18 of the general machine-frame, and the purpose of removing the holders 34 and supporting them upon the studs 30 is to enable 90 the convenient replenishing of the chocolates or other goods to said holders, after which the holders will be restored to their normal position. (Illustrated in Fig. 7.) 95

The interior operative mechanism of the machine is mounted upon the shaft 27, and since this shaft is carried by the front section 22 the latter carries all said mechanism, and hence upon the removal of the section 20 from the machine the entire operative mechanism is thereby withdrawn, this being of advantage in the assembling of the machine and also in the event that any repairs may be necessary in such mechanism, it being convenient in accordance with my invention to remove the section 20 and all of the interior mechanism and substitute another section 20 carrying a duplicate of such mechanism in good operative condition. 100

The section 20 is formed near its upper edge with coin-admission slots 42 and windows 43, the latter being closed by glass or other transparent substance. The section 22 is also formed with customary slots 44 for the operating-levers 45, and said section 22 is at a suitable point above the lower ends of the slots 44 formed with the transversely-aligned apertured lugs 46, through which when it is desired to tilt said section to the position shown in Fig. 6 will be passed a wire rod for the purpose of holding all of the levers 45 in their lower or depressed position at the lower ends of the slots 44, the purpose of thus locking the levers 45 at their lower position when 115 it is desired to tilt the section 22 being merely for the purpose of preventing the inner ends of the ejectors 47 from slipping downwardly toward the front from off of the supporting-strip 26, fastened to the transverse bar 25. 120

125

130

Should the said ejectors thus turn downwardly from the strip 26 when the section 22 is tilted to discharge the coins, some difficulty might be experienced in restoring the 5 ejectors to position upon said strip when it is desired to move the lower end of said section 22 inwardly to its normal position against the bar 25. The sole purpose of the lugs 46 is therefore to receive a wire rod for locking the 10 levers 45 in their depressed position, and the sole object in thus locking the said levers is to prevent the ejectors 47 from slipping off from the strip 26 when the upper end of the front section 22 is moved inwardly to the position 15 shown in Fig. 6.

In the present instance I present a machine having two holders 34 for the stacks of condiments and two operating-levers 45 for coöperation with said holders, one lever and its 20 parts being provided for each holder; but in practice the machine may have as many holders 34 and as many operating-levers 45 as may be required to suit the occasion. Each lever 45, with its coöperating parts, is a 25 duplicate of every other lever 45 and its coöperating parts, and hence a description of the construction and operation of one lever 45, with its parts, will be sufficient for the purposes of this case.

30 The lever 45 projects outwardly through a slot 44 in the front section 22 and is integral with a segmental frame 50, which is in the form of a cast plate having on the side face thereof a chute 51 for coins and embodying a rear stop-arm 52, forwardly-projecting finger 53, and downwardly-extending arm 54, to which is pivotally secured the ejector 47, this ejector having at its outer or front end an inclined plate 55, which operates as a coin-receiver and from which the coin is finally removed by means of the finger 53, the point of the latter, when the lever 45 is depressed, passing through an opening 56 in said plate, Figs. 5 and 10, and pushing the coin therefrom, so that the coin may fall downwardly, as shown in Fig. 4, into the receptacle formed above the inwardly-extending portion of the section 22.

The construction and operation of the ejector 47 and coin-receiving plate 55 will be described hereinafter, it being sufficient at present to say that the plate 55 and ejector 47 constitute a coin-testing frame in which the coin is tested both as to its size and weight 55 and if found deficient in either respect fails to operate the ejector to detach a piece of material 37 from the stack. The frame 50 is formed with a hub 57, by which the frame is mounted upon the shaft 27, and at its outer 60 curved or segmental edge the said frame is formed with the transverse flanges or plates 58 59, which ride within the upper curved portion of the section 22 and between which is formed the slot 60, leading to the chute 51, 65 and which slot in the initial condition of

frame 50 stands in line with the slot 42 in said section 22, so that a coin may be introduced through the slots 42 60 and enter said chute. In the normal condition of the frame 50 the plate 59, formed thereon, will stand in line with the window 43 and, as shown at the left-hand side of Fig. 1, will bear a word descriptive of the contents of the holder 34 with which said frame coöperates. The plate 58, formed on the frame 50, will normally stand 70 above the coin-slot 42 of the section 22, as shown in Fig. 2, and upon this plate 58 I have printed the word "Empty," which word will appear at the window 43 when the lever 45 is in its lower position and will remain at said window when the holder 34 becomes empty or requires replenishing, at which time the lever 45 will be locked in its lower position, as shown in Fig. 4, by reason of the fact that the follower-weight 61, resting upon the stack of 75 confections 37, will at the proper time carry its arm 62 downwardly in line with the stop 52, formed on the frame 50, said arm 62 at such time preventing the return of the lever 45 to its upper position and locking the frame 50 in its depressed position, this being for the purpose of locking the plate 58 in position to expose the word "Empty" at the window-opening 43 and close the entrance-slot 42 for coins. The frame 50 is held in its normal position, with the chute 51 below the coin-receiving slot 42, by means of a coiled spring 63, whose upper end is fastened on a pin connected with the section 22 and whose lower end is fastened upon a pin formed on the face of the frame 50. When the lever 45 is depressed, the frame 50 turns downwardly, and when the lever 45 is released the spring 63 returns the frame 50 to its normal upper position.

The chute 51 curves frontwardly, and its inner wall 64 at its lower end is cut away or recessed on the arc of a circle, as denoted in Fig. 3 at 65. Below the lower end of the chute 51 the frame 50 is provided with a transverse plate 66, which has a convex inner upper surface or edge and is formed with a stud 67. The coins which slide downwardly through the chute 51 fall upon the plate 66 and thence tilt inwardly and fall therefrom and are caught by the plate 55, as shown in Fig. 2. The stud 67 is provided upon the plate 66, so that should a washer in lieu of a coin be fed to the machine such washer will be caught upon the plate 66 by reason of the stud 67 entering the opening 110 115 therein.

The proper coins which pass downwardly through the chute 51 and fall upon the curved plate 66 and are thereby tilted inwardly fall therefrom by gravity against the face of the 120 plate 55 and are caught by the latter, said plate 55 having at one edge a hook 68 and at its opposite edge a finger 69 to catch and retain a coin, said parts 68 and 69 being sufficiently separated to just hold a coin without 125 130

letting the latter slip downwardly between the same. The plate 55 is integral with the ejector 47, and the latter is secured upon the pivot-pin 70, so that said ejector and plate 5 constitute an integral pivotally-mounted frame whose inner portion is heavier than its outer portion and normally rests upon the metal strip 26, hereinbefore referred to and as shown by dotted lines in Fig. 2. 10 When a coin of the proper weight is caught by the plate 55, it will tilt the front end of the ejector 47 downwardly, and thereby move the rear end of said ejector upwardly to the position shown by full lines in Fig. 2 in line with the lower piece 37 of the condiments, and then when the operating-lever 45 is depressed to turn the frame 50 downwardly on the shaft 27 the arm 54 of said frame will drive the ejector 47 inwardly and 15 cause the same to move the lower piece 37 from the stack, as represented by the dotted lines in Fig. 4. During the inward movement of the ejector 47 under the action of the arm 54 the finger 53 of the frame 50 turns downwardly and its end passes through the opening 56 in the plate 55 and pushes the coin from the hook 68 and finger 69, as shown in Fig. 4. If the coin fed to the machine had been deficient in weight, it would not have 20 tilted the front end of the ejector and testing-frame downwardly, and hence the inner end of said frame would not have turned upwardly into position to dislodge a piece of the condiment, but would have passed inwardly 25 below the stack, and the finger 53 would have ejected such coin, and if the coin fed to the machine had been deficient in size it would not have been caught by the hook 68 and finger 69, but would have slipped between the 30 same and passed into the general receptacle for coins. The frame formed of the ejector 47 and plate 55 thus tests the coins both as to weight and size and fails to operate if a coin fed to the machine is deficient in either 35 weight, diameter, or thickness. The testing of the coin as to its thickness is rendered possible from the fact that the hook 68 stands at an oblique angle to the face of the plate 55, that a coin of proper thickness and diameter 40 resting against the face of the plate 55 will engage the hook 68 at a point about, say, midway between the ends of the latter and become caught, and that a thin disk of the same diameter will not be able to thus engage 45 the hook 68 and will consequently slip down between the plate and hook. 50 The machine is also equipped with means for preventing its operation with the use of a steel disk, and these means comprise ordinary magnets 71 and a bar 72, which is employed in connection with screws 73 for securing the magnets 71 to the front section 22. The bar 72 is formed with upwardly and inwardly deflected fingers 74, which are in line 55 with the lower end of the frames 50, each

frame 50 being formed with a space between the side wall 75 of the chute 51 and the adjacent edge of the convex plate 66 to admit a finger 74, Fig. 2. When the frame 50 is in its normal position, the upper end of the finger 74 therefor stands within the said space between the side wall 75 and convex plate 66, as shown in Fig. 2, and when the frame 50 is turned downwardly, as illustrated in Fig. 4, the said finger 74 remains stationary and the frame 50 passes downwardly over it, so that anything then resting on the convex plate 66 would be disturbed and pushed therefrom by being carried downwardly against the said finger 74. When a steel disk is fed to the chute 51, it slides downwardly and before turning inwardly upon the plate 66 is caught at its edge by the magnet 71, as shown in Fig. 2, the magnet holding the steel disk and preventing it from turning inwardly and reaching the plate 55. When the steel disk, which I number 85, is in the position shown in Fig. 2 and the frame 50 is then depressed, the downward movement of the frame will carry the plate 66 from the disk, and the disk will be caught at one lower edge by the finger 74 and at its upper opposite edge by a stud 76, carried by the frame, and thus detached from the magnet 71 and caused to fall downwardly into the receptacle for coins, said disk not falling over the inner or rear edge of the plate 66, but over the outer or front edge thereof. The finger 74 and stud 76 also coöperate to detach washers or the like from the plate 66. If a washer or piece of metal having a hole in it is fed to the machine and not caught by the magnet, but by the stud 67, which is upon the upper surface of the plate 66, it will upon the depression of the operating-lever 45 be carried against the finger 74 and the stud 76 will be carried against it and said washer will be detached from the plate 66 and descend into the general receptacle for coins, said washer not passing over the inner or rear edge of the plate 66, but over the outer edge thereof.

After the machine has been operated for a definite period the coins should be removed therefrom and the holders 34 replenished with condiments or other articles, and in carrying out these purposes I first unlock and remove the upper front section 20 and then elevate the holders 34 to the position shown in Fig. 6, in which position the said holders may be conveniently replenished with the goods, as sufficiently hereinbefore described. When the holders 34 are in their upper position, (shown in Fig. 6,) I first lock the levers 45 in their depressed position, as hereinbefore explained, and then push the upper end of the casing-section 22 inwardly or tilt said section upon the shaft 27 to the position shown in Fig. 6, so that the coins may slip from the member 23 of said section 22 and fall upon the floor of the machine or upon a suitable

pan or receiver introduced over said floor. After the holders 34 have been replenished and the coins have been removed from the machine I restore the section 22 to its normal position and return the holders 34 to their normal position and then restore the front section 20 and lock the same. In the event that any repairs are necessary to the interior mechanism the front section 22 will be lifted from the general frame of the machine and a new section 22, carrying a set of the mechanism, will be introduced to the machine. The section 22 carries all of the interior operative mechanism, and this is a very great convenience both in the assembling of the machines and in case of necessity to repair the same.

The operation of the machine will be fully understood from the detailed description hereinbefore presented, and hence I will simply call attention to the simplicity and efficiency of the machine. Each set of the operative mechanism comprises simply the frame 50 carrying the combined ejector and coin receiving and testing frame, and this frame 50 is mounted on the shaft 27, which is carried by the front section 22. The frame 50 is preferably a casting, and the ejector 47 and plate 55 are preferably formed from one integral piece of sheet metal and pivoted to the arm 54 of said frame 50.

What I claim as my invention, and desire to secure by Letters Patent, is—

1. In a vending-machine, the general cabinet or casing containing holders for the stacks of articles to be sold and having at its lower front vertical portion the front section 22 provided with an inwardly-extending lower member 23 above the discharge-passage for the goods sold, said front section forming with in it a chamber to contain the operative mechanism and receive the coins, the latter being received upon said member 23, combined with means pivotally mounting said front section so that at the proper time the lower end thereof may be turned outwardly toward the front for enabling said member 23 to discharge the coins, and means for normally locking said front section 22 in rigid position; substantially as set forth.

2. In a vending-machine, the general cabinet or casing containing holders for the stacks of articles to be sold and having the pivotally-mounted lower front section forming within it a chamber to contain the operative mechanism and receive the coins, means intermediate the upper and lower ends of said front section for pivotally mounting the same, means for preventing the lower end of said section from being pushed inwardly, means for normally preventing the upper end of said section from being pushed inwardly and means for releasing the upper end of said section so that it may be pushed inwardly for tilting said section on its bearings and there-

by effecting the discharge of the coins; substantially as set forth.

3. In a vending-machine, the general cabinet or casing containing holders for the stacks of articles to be sold and having the pivotally-mounted lower front section forming within it a chamber to contain the operative mechanism and receive the coins, said section having an inwardly-extending lower member, combined with a transverse bar to be normally engaged by said member, and a removable front section adapted to be locked within the casing and to engage the upper edge of said section for locking the latter stationary, said section at its upper edge and said removable front section having interengaging surfaces for preventing the movement of either of said sections, said pivotally-mounted section being capable of being tilted inwardly to discharge the coins when the said removable front section is withdrawn from the casing; substantially as set forth.

4. In a vending-machine, the general cabinet or casing containing the holders for the stacks of articles to be sold and the pivotally-mounted lower front section for said cabinet and forming within it a chamber to contain the operative mechanism and receive the coins, a transverse bar normally engaged by the lower end of said front section, the removable front 20 which normally engages the upper edge of said front section and locks the same; and means for locking said front, said front having hooks 31 to engage studs 30 provided in the casing; substantially as set forth.

5. In a vending-machine, the general cabinet or casing containing operative mechanism for receiving and testing the coins and dislodging the articles to be sold, the holders for the stacks of said articles, hooks carried by said holders for engaging supports therefor when said holders are in their normal position and studs located at a higher elevation in said casing for receiving said hooks when it is desired to partly remove said holders and replenish them with goods, said cabinet or casing having a removable front; substantially as set forth.

6. In a vending-machine, a holder for the articles to be sold, a pivotally-mounted frame affording a coin-chute and having an exposed handle whereby said frame may be manually turned on its pivot, and an ejector pivotally secured to and carried by said frame at a point below said chute, said ejector having means adjacent to the lower end of said chute for receiving the coin and holding the same and being so balanced that the coin, if of proper weight, will tilt said ejector into its operative position with relation to the lower end of said holder, whereby on the movement of said pivoted chute-frame said ejector will be moved to dislodge the article sold; substantially as set forth.

7. In a vending-machine, a holder for the

articles to be sold, a pivotally-mounted frame affording a coin-chute and having an exposed handle whereby said frame may be manually turned on its pivot, and an ejector pivotally secured to and carried by said frame at a point below said chute, said ejector having means adjacent to the lower end of said chute for receiving the coin and holding the same and being so balanced that the coin, if of proper weight, will tilt said ejector into its operative position with relation to the lower end of said holder, whereby on the movement of said pivoted chute-frame said ejector will be moved to dislodge the article sold, combined with means to dislodge the coin from said ejector during the movement of the same with said frame; substantially as set forth.

8. In a vending-machine, a holder for the articles to be sold, a pivotally-mounted frame affording a coin-chute and having an exposed handle whereby said frame may be manually turned on its pivot, and an ejector pivotally secured to and carried by said frame at a point below said chute, said ejector having means adjacent to the lower end of said chute for receiving the coin and holding the same and being so balanced that the coin, if of proper weight, will tilt said ejector into its operative position with relation to the lower end of said holder, whereby on the movement of said pivoted chute-frame said ejector will be moved to dislodge the article sold, said means for receiving and holding the coin comprising a plate having members at its opposite edges between which the coin passes and which, if the coin is of proper dimensions, will hold the same; substantially as set forth.

9. In a vending-machine, a holder for the articles to be sold, a pivotally-mounted frame affording a coin-chute and having an exposed handle whereby said frame may be manually turned on its pivot, and an ejector pivotally secured to and carried by said frame at a point below said chute, said ejector having means adjacent to the lower end of said chute for receiving the coin and holding the same and being so balanced that the coin, if of proper weight, will tilt said ejector into its operative position with relation to the lower end of said holder, whereby on the movement of said pivoted chute-frame said ejector will be moved to dislodge the article sold, said means for receiving and holding the coin comprising a plate having an oblique hook at one edge and a finger at the other edge between which hook and finger the coin will pass and which will hold the same if the coin is of proper thickness and diameter; substantially as set forth.

10. In a vending-machine, a holder for the articles to be sold, a movable frame affording the coin-chute which extends downwardly and outwardly toward the front wall of the machine, a transverse inwardly and downwardly extending plate below said chute and

upon which the coins fall from said chute and which tilts said coins backwardly therefrom, and an ejector pivotally secured to and carried by said frame at a point below said chute and below the inner edge of said plate, said ejector having means adjacent to the inner edge of said plate for receiving a coin therefrom and holding the same and being so balanced that the coin if of proper weight will tilt said ejector with relation to the lower end of said holder, whereby on the inward movement of said ejector due to the movement of said frame the ejector will dislodge the article sold; substantially as set forth.

11. In a vending-machine, a holder for the articles to be sold, a pivotally-mounted frame carrying a chute to receive the coins from the coin-slot, means for operating said frame, and an ejector pivotally mounted on said frame and having at one end means for receiving and holding a coin and being so balanced that the coin, if of proper weight, will tilt said ejector into its operative position, said frame having means at the lower end of said chute for directing the coin to said receiving and holding means; substantially as set forth.

12. In a vending-machine, a holder for the articles to be sold, a pivotally-mounted frame carrying a chute to receive the coins from the coin-slot, means for operating said frame and a coin-controlled ejector carried by said frame for dislodging the articles sold, said frame having a stop 52, combined with a follower 61 mounted upon the stack of articles in said holder and having an arm 62 which, upon the depression of said frame at the time said holder should be replenished, will pass into engagement with said stop for locking said frame in an inoperative position; substantially as set forth.

13. In a vending-machine, a holder for the articles to be sold, a pivotally-mounted frame carrying a chute to receive the coins from the coin-slot, means for operating said frame, and a coin-controlled ejector for dislodging the articles as sold, said frame having a plate 58 which closes said coin-slot when said frame is operated, combined with means for locking said frame in its operative position with said plate closing said slot when said holder should be replenished; substantially as set forth.

14. In a vending-machine, a holder for the articles to be sold, a pivotally-mounted frame carrying a chute to receive the coins from the coin-slot, means for operating said frame, and an ejector pivotally mounted on said frame and having at one end means for receiving and holding a coin and being so balanced that the coin, if of proper weight, will tilt said ejector into its operative position, said frame having means at the lower end of said chute for directing the coin to said receiving and holding means, and said machine being pro-

vided with a support for the inner end of said ejector when the latter is not in its operative position; substantially as set forth.

15. In a vending-machine, a holder for the articles to be sold, a pivotally-mounted frame carrying a chute to receive the coins from the coin-slot, means for operating said frame, and an ejector pivotally mounted on said frame and having at one end means for receiving and holding a coin and being so balanced that the coin, if of proper weight, will tilt said ejector into its operative position, said frame having means at the lower end of said chute for directing the coin to said receiving and holding means, and said machine being provided with a support for the inner end of said ejector when the latter is not in its operative position; combined with means for locking said pivotally-mounted frame in its operated position when so desired; substantially as set forth.

16. In a vending-machine, a holder for the articles to be sold and a pivotally-mounted frame 50 comprising the chute 51, plate 66 at the lower end of said chute to receive the coins, a downwardly-extending arm 54, a forwardly-extending finger 53 and an operating-lever 45, combined with a pivotally-mounted ejector carried by said arm 54 and having adjacent to said plate 66 coin-receiving means, said finger 53 being adapted to dislodge the

coin from said coin-receiving means when said lever is operated; substantially as set forth.

17. In a vending-machine, the front casing 35 having the coin-slot and window, a holder for the articles to be sold, and a pivotally-mounted frame carrying a chute to receive the coins from said slot and having an operating-lever projected through said casing, said 40 frame also having plates 58, 59 between which a slot is provided to receive the coins and direct them into said chute, said plate 59 being normally at said window and said plate 58 normally closing the coin-slot when said 45 lever is operated, combined with an ejector carried by said frame and provided with means for receiving the coin fed through said chute, means for dislodging the coin from said receiving means and means for locking 50 said frame in its operated position with said plate 58 closing the coin-slot when said holder should be replenished; substantially as set forth.

Signed at New York city, in the county 55 and State of New York, this 18th day of May, A. D. 1905.

ELIJAH F. SPAULDING.
